Primary Examiner — Nathan M Johnston

(57) **CLAIM**

The ornamental design for a nasal spray guide, as shown and described.

DESCRIPTION

FIG. 1 is an upper perspective view of a nasal spray guide showing the new design;

FIG. 2 is a lower perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof;

FIG. 8 is a bottom plan view thereof;

FIG. 9 is a front view of the nasal spray guide before being installed on a nasal spray dispenser;

FIG. 10 is a front view of the nasal spray guide partially installed on a nasal spray dispenser; and,

FIG. 11 is a front view of the nasal spray guide fully installed on a nasal spray dispenser.

The broken lines are for the purpose of illustrating the environment in which the design is used and form no part of the claimed design.
